[57] **CLAIM**

The ornamental design for a hand powered massager, as shown and described.

DESCRIPTION

FIG. 1 is a front, top and side perspective view of the hand powered massager showing my new design;
FIG. 2 is a front elevational view thereof, the rear being a mirror image of the front shown in FIG. 2;
FIG. 3 is an end elevational view thereof, the end opposite being a mirror image of the end shown in FIG. 3;
FIG. 4 is a top plan view thereof; and,
FIG. 5 is a bottom plan view thereof.

FIG.1.
